Inventor

J. W. Nippert,

UNITED STATES PATENT OFFICE.

JOHN W. NIPPERT, OF NEW BRIGHTON, PENNSYLVANIA.

SPRING-WHEEL.

1,107,439.

Specification of Letters Patent. Patented Aug. 18, 1914.

Application filed October 28, 1912. Serial No. 728,230.

To all whom it may concern:

Be it known that I, JOHN W. NIPPERT, a citizen of the United States, residing at New Brighton, in the county of Beaver and State of Pennsylvania, have invented certain new and useful Improvements in Spring-Wheels, of which the following is a specification, reference being had to the accompanying drawings.

10 The present invention relates to new and useful improvements in spring wheels designed to be used in conjunction with motor vehicles or the like and the primary object of the present invention is to provide a cushioning device for wheels of this character which is composed of a plurality of sections whereby the same may be easily and readily removed and new sections substituted in their place should the same become 15 worn or broken thereby increasing the life 20 of the wheel.

Another object of the present invention is to provide a device of this character which will be comparatively inexpensive in the cost 25 to manufacture, strong, durable, and efficient when in use, and having the parts thereof adapted to be readily assembled and installed thereby rendering the device commercially desirable.

30 With the above and other objects in view the invention consists of the novel details of construction, combination, formation, and arrangement of parts as will be hereinafter more fully described and particularly pointed 35 out in the accompanying drawings in which—

Figure 1 is a side elevation of the wheel having portions of the outer plate removed therefrom, Fig. 2 is a vertical section 40 through the same, Fig. 3 is a detail sectional view on the line 3—3 of Fig. 1, Fig. 4 is a horizontal sectional view through one of the jacks, and Fig. 5 is a detail perspective view.

45 Reference now being had to the accompanying drawings wherein like and corresponding parts are designated by similar reference characters throughout the several views the wheel comprises an ordinary hub 50 1 having secured thereto a plurality of radially extending spokes 2 being secured at their outer end to a rim 3. An outer rim 4 is spaced from the rim 3 by means of my improved cushioning device and is adapted 55 to be secured thereto as will be hereinafter more fully described.

The cushioning device proper forming the subject matter of the present invention comprises a band 5 which is adapted to rest upon the outer periphery of the inner rim 3 having secured thereto a plurality of sections forming the cushioning device between the inner and outer rims 3 and 4 respectively which also holds the rims in proper position.

60 The sections of the cushioning device comprise outer and inner rim sections 6 and 7 respectively which are preferably made of segmental pieces of flat metal. Formed upon the inner face of each of the rim sections 6 and 7 respectively are a plurality of 65 alining recessed projections 8 in each of which is adapted to rest a coil spring 9. It is apparent from the foregoing that in assembling the wheel the inner shoe 7 is secured to the outer periphery of the band 5 70 by means of rivets 10 or the like and the coil springs are placed between the two rim sections and thence the outer rim section 6 rests 75 upon the inner periphery of the outer rim 4.

Owing to the expansion of the coil 80 springs 9 it is found to be a difficult matter to insert the cushioning devices between the inner and outer rims 3 and 4 respectively and so I have provided within each section 85 a pair of detachably mounted jacks 11 which will act against the expansion of the coil 90 spring and permit the sections of the cushioning device to be readily inserted in place. Formed integral upon the opposing faces of the rim sections 6 and 7, respectively, are 95 alining recessed bosses 12 and 13, respectively, which are positioned between the recessed projections 8, as shown. An adjustable screw 14 is adapted to be mounted within each of the bosses 12 and 13 so that 100 when the coil springs 9 are placed between said rim sections, the screw 14 may be adjusted until the distance between the two rim sections 6 and 7 is less than the distance between the rims 3 and 4, thereby permitting 105 the sections 6 and 7 to be easily and readily placed in position. After sections 6 and 7 are placed in position between the rims 3 and 4, the screws 14 are removed, thereby permitting the coil springs 9 to expand and 110 hold the rims 3 and 4 in proper spaced relation and serve as cushioning means between said rims 3 and 4. Each of the screws 110 14 comprises a cylindrical shank having a hexagonal nut 15 formed integral with the medial portion thereof and a threaded portion 16 which is adapted to be inserted in

115

the recessed bosses 12 while the opposite end of the screw 14 is adapted to rest within the alining bosses 13. The screw 14 is also provided with an annular groove 17 which is adapted to be in alinement with the openings 18 formed in the bosses 13, whereby a pin 19 may be inserted through said openings, to lock the screw 14 in position. It will be manifest that after removing the pins 19, the 10 screws 14 may be readily removed. The screws 14 are preferably removed from one section at a time. To provide means for preventing dirt and other foreign matter from accumulating between the sections of 15 the cushioning device, I inclose the same by side plates 20 secured upon each side of the vehicle wheel, the inner marginal edges of said plates being permanently secured to the inner rim 3 by securing members 21 or the 20 like, while the outer edges of said plates project beyond the outer rim section 6. The side plates 20 are connected intermediate of their inner and outer edges by the connecting members 22 extended between the outer 25 and inner rim sections 6 and 7 and between the springs 9 and screws 14, as will be clearly understood by referring to Fig. 1 of the drawing.

While from the foregoing I have described 30 and shown the specific embodiment of the

present invention it is of course to be understood that other minor details as to changes, formation, alteration and modification may be resorted to that come within the scope of the present invention without departing 35 from the spirit thereof or sacrificing the efficiency of the same.

What I claim is:

A device of the class described, comprising the combination of an inner rim, a sectional outer rim, a tread member engaged upon the sectional outer rim, cushioning members between said inner and outer rims, outwardly directed flared smooth sockets carried on the inner rim, inwardly directed 40 threaded sockets carried on the sections of the outer rim, said smooth and threaded sockets being positioned opposite one another and adapted to receive a removable assembling tool, and a securing pin removably engaged transversely through one side of each smooth socket to lock the tool in position.

In testimony whereof I hereunto affix my signature in the presence of two witnesses. 55

JOHN W. NIPPERT.
